UNITED STATES PATENT OFFICE.

HARRY A. WILLIAMS, OF PENACOOK, NEW HAMPSHIRE.

PICKER-STICK CHECK FOR LOOMS.

SPECIFICATION forming part of Letters Patent No. 448,309, dated March 17, 1891.

Application filed April 28, 1890. Serial No. 349,776. (No model.)

To all whom it may concern:

Be it known that I, HARRY A. WILLIAMS, a citizen of the United States, residing at Penacook, in the county of Merrimac and State of New Hampshire, have invented certain new and useful Improvements in Picker-Stick Checks for Looms, of which the following is a specification.

This invention relates to the picker-stick checks for looms, the object being to provide a cushion or yielding stop device, against which the picker-stick may strike and prevent its tendency to rebound, which frequently causes the yarn to slide off from the bobbin in the shuttle.

The invention will be fully set forth in the specification and claim, and clearly illustrated in the accompanying drawings, forming an inseparable part thereof, of which—

Figure 1 shows an end view of the lathe of a loom having my improved device attached. Fig. 2 is an elevation, partly in section, of one end of the lathe, showing the picker and a portion of the picker-rod, shuttle-box, shuttle, and picker-stick, and my improved device mounted upon the under side of the lathe in its proper relative position. Fig. 3 is an enlarged side elevation of my improved attachment as detached. Fig. 4 represents the same in plan. Fig. 5 is a cross-section of one end of that part of my attachment which is attached to the lathe.

Similar reference-letters designate like parts in all the figures.

A represents the lathe of a loom; B, an end casting, in which is mounted one end of the picker-rod *b*.

C C are the channel-bars, which form the sides of the shuttle-box.

D represents the shuttle; E, the picker; F, the picker-stick, and *f* the strap connecting the two latter.

My improved attachment consists of a casting *G*, provided with right-angled projections *g*, one at each end, in which is mounted a rod *H*, on which is placed a collar *I* between said projections and having a helical spring *J* operating expansively between said collar and one of the bearings *g*. Said collar may, if preferred, be loosely mounted upon the rod *H* and provided with a set-screw *I'*, as shown, by which it may be adjusted in order

to increase or diminish the tension of said spring *J*, for a purpose to be hereinafter specified.

55

Upon one end of the rod *H* is mounted the stop-piece *K*, its normal position being horizontal, as shown, and in order that such position may be maintained one end of the rod *H* may be square, as shown in Fig. 2, and its bearing in the projection *g* is likewise square, as seen in Fig. 5.

The outer end of the stop-piece is provided with two forwardly-projecting lugs or ears *kk*, one of which fits close against the side of one of the bearings or projections *g* when in its normal position or at rest, and the other ear is far enough away from or beyond the first ear to form a notch or recess *k'* just the width of the picker-stick, which fits within it. By arranging the ears as above described the inner ear will assist in preventing the rotation of the rod by resting against the side of the bearing when the laterally-projecting stop-piece is struck by the stick in its outward movement, and by having the stick strike between the two ears the rotation of the rod will be prevented after the inner ear has been forced away from the bearing *g*, as the ears will engage with the opposite sides of the stick and prevent the twisting of the rod by the downward pressure of the end of the stick as it is being swung around with its pivotal point at the opposite end for a center. The ears may be flattened or made wider and rounding, if desired, so that they will present a greater surface to the sides of the stick and will not wear it as they would do if they were square or had sharp corners.

The bed-casting *G* is perforated at intervals, as shown in Fig. 4, through which to insert screws for attachment to the lathe.

In use the picker-stick strikes between the ears *kk* and moves the rod *H* slightly in the direction of the arrows. Should the spring *J* become weak, so that the blow of the picker-stick moves the rod *H* too freely, the collar *I* may be adjusted closer to the stop *K*, and vice versa.

By constructing the check as above described it can be attached to the ordinary looms without any alterations, except the holes in the loom for the holes for the screws to hold the bed-casting in place, and it can

be attached to the under side of the lathe, so that it is entirely out of the way and will not present any points or projections for catching the thread or clothes of the operators. 5 It is complete and compact, and the ears forming the recess between them for the reception of the picker-stick will engage with the sides of the stick, and thus assist in preventing the rod from turning, which it has a 10 tendency to do from the stick acting upon it at one side.

Having described my improvement, what I claim is—

15 The combination, in a picker-stick check for looms, of a bed-casting adapted to be secured to the lathe of a loom and having a

right-angled projection at each end, a spring-actuated rod mounted therein having a laterally-extending stop-piece secured to one end, said stop-piece having two forwardly-extending ears, one of which fits close against the side of one of the projections or bearings upon the bed-casting, and the other one is far enough away from or beyond the first ear to form a recess for the reception of the picker-stick, substantially as described. 20 25

In testimony whereof I affix my signature in presence of two witnesses.

HARRY A. WILLIAMS.
